UNITED STATES PATENT OFFICE.

WALTER B. ROGERS, OF KNOXVILLE, TENNESSEE.

TRACK-SANDER.

1,088,935.

Specification of Letters Patent.

Patented Mar. 3, 1914.

Application filed October 1, 1912, Serial No. 723,454. Renewed December 30, 1913. Serial No. 809,592.

To all whom it may concern:

Be it known that I, WALTER B. ROGERS, citizen of the United States, residing at Knoxville, in the county of Knox and State of Tennessee, have invented certain new and useful Improvements in Track-Sanders, of which the following is a specification.

This invention relates to track sanders for locomotives and other railway rolling stock. 10 The primary object of the invention is to provide a track sander of simple and durable construction in which clogging or choking of the air passage in the blast nozzle by back pressure of the sand from the reservoir 15 during the sanding operation is effectually prevented.

A further object of the invention is to provide a sanding device, the construction of which is such that when air or other fluid 20 is admitted to the blast nozzle any particles of sand or foreign matter which may find lodgment in the air passage of the nozzle will be automatically discharged, thus rendering the device self-cleaning.

25 A further object is to provide a blast nozzle capable of being readily removed from the casing to permit cleaning or renewal thereof without the necessity of entirely detaching the nozzle clamping means; which 30 cannot be incorrectly positioned within the casing and which will be held against accidental displacement should the nozzle clamping means for any reason work loose.

35 A further object is to provide means for centering the discharge end of the blast nozzle within the sand passage of the casing, thus to afford ample clearance around the nozzle for the discharge of stones, gravel and the like which may be drawn from the 40 sand box by the action of the blast.

A further object is to provide the sand passage at a point remote from the discharge end of the nozzle with an upstanding lip defining a contracted throat which 45 prevents the sand from discharging from the box or reservoir when the blast is cut off and serves to direct the volume of sand against a suitable deflector when the blast is admitted to the nozzle, thereby preventing 50 abrading action of the sand on the interior walls of the casing and consequently materially prolonging the effective life thereof.

55 A further object is to provide a blast nozzle having a novel form of strainer at one end thereof and a cleaning plug at the other, the intermediate portion of the nozzle being

deflected laterally so as to prevent the sand from coming in contact therewith.

A still further object of the invention is generally to improve this class of devices so as to increase their utility, durability and efficiency. 60

Further objects and advantages will appear in the following description, it being understood that various changes in form, 65 proportions and minor details of construction may be resorted to within the scope of the appended claims.

For a full understanding of the invention and the merits thereof, reference is to be had 70 to the following description and accompanying drawings, in which:

Figure 1 is a perspective view of a track sander constructed in accordance with the present invention; Fig. 2 is a vertical sectional view thereof; Fig. 3 is a transverse sectional view taken on the line 3—3 of Fig. 2 and looking in the direction of the arrow; Fig. 4 is a perspective view of the blast nozzle detached; Fig. 5 is a similar 75 view of the bushing, showing the strainer in position thereon; Fig. 6 is an enlarged longitudinal sectional view, showing the manner of clamping the nozzle in position on the casing and also illustrating the construction of the strainer; Fig. 7 is a perspective view of the deflector carrying cap detached. 80

Corresponding and like parts are referred to in the following description and indicated in all the views of the drawings by 85 the same reference characters.

The improved track sander forming the subject matter of the present invention comprises a hollow body portion or casing 5 95 having angularly disposed nipples 6 and 7, one of which is exteriorly threaded for connection with a sand box 8 and the other interiorly threaded for attachment to a correspondingly threaded discharge pipe (not 100 shown). The nipple 6 is provided with a sand passage 9 which communicates with the interior of the sand box and casing, respectively, the lower wall of the inlet passage 9 at the outer end thereof being curved or 105 deflected upwardly to produce a contracted throat 10 which serves to concentrate the sand from the box and direct said sand against the adjacent face of a suitable deflector, indicated at 11. The deflector 11 is 110 of the construction shown in Fig. 7 of the drawings and comprises essentially a metal

disk having an angular shank 12 projecting from one face thereof and provided with terminal threads 13 for engagement with a clamping nut 14.

- 5   Mounted on the angular shank 12 of the deflector, is a threaded cap 15 which engages a correspondingly threaded opening 16 formed in the casing at a point opposite the sand passage 9, there being a packing strip 10 or washer 17 interposed between the body 11 of the deflector and cap 15 as best shown in Fig. 2 of the drawings. The active face 18 of the deflector is preferably disposed above and at an angle to the longitudinal axis of the nipple 7 so that the sand discharged through the passage 9 will be forced against the face 18 and thence be deflected downwardly through the nipple 7 to the conductor leading to the track. The cap 15 is provided with an opening, the walls of which are angular to conform to the angularity of the shank 12 so that after one portion of the face 18 of the deflector has become worn by contact with the sand a new or fresh face 15 may be presented to the sand by releasing the nut 14 and partially rotating the deflector, the latter being clamped in adjusted position by tightening the nut 14 as will be readily understood.
- 20   The casing 5 is provided with an extension 19 in which is seated a blast nozzle 20, the free end of the extension being provided with a flat bearing surface 21 having an opening 22 formed therein to permit the insertion of said blast nozzle. The blast nozzle 20 is in the form of a tube having one end thereof provided with a head 23 which fits within the opening 22 and is formed with a laterally extending flange 24, the 25 lower face of which is provided with an annular groove adapted to receive a correspondingly shaped rib 25 on the bearing surface 21, thus to provide a tight joint and effectually prevent the entrance of water or moisture to the interior of the casing. The head 23 is provided with an angular extension 26 having a threaded socket formed therein for engagement with a correspondingly threaded bushing 27, the inner 30 end of said bushing being provided with an annular shoulder 28 which forms a seat for a strainer, indicated at 29. The strainer 29 is in the form of a cup and is provided with a laterally extending flange 30 which 35 bears against the shoulder 28 and is held against accidental displacement by a nipple or gland 31 to which is attached a pipe 32 leading to a source of air or other fluid pressure.
- 40   It will here be noted that by forming the strainer 29 with the flange 30 for engagement with the nipple 31, not only is the strainer locked against accidental displacement, but the entrance of dust and other 45 foreign particles around the edges of the

strainer to the active end of the nozzle is effectually prevented. Further by reason of the fact that the strainer 29 rests on the shoulder 28, the nipple 31 and bushing 27 carrying the strainer 29 may be simultaneously detached from the blast nozzle, thus preventing loss of the strainer.

The inner end of the nozzle 20 extends longitudinally beyond the inner end of the 50 nipple 6 and preferably projects a short distance within the sand box 8, there being a curved depression or seat 33 formed in the upper wall of the sand passage 9 for the reception of the tubular body of the nozzle, 55 as shown in Fig. 3 of the drawings. Depending from and preferably formed integral with the tubular body portion of the nozzle 20, is an enlargement 34 having tapered side walls and provided with intersecting passages 35 and 36 which communicate with the central bore 37 of the nozzle, the passages 35 and 36 being of uniform diameter and of less diameter than that of the bore 37.

The air passage or duct 35 extends longitudinally of the enlargement or nozzle proper 34, while the passage or duct 36 is inclined rearwardly and intersects the passage or duct 35 at a point near the rear 60 end of the enlargement. By such a construction a portion of the air from the bore 37 will be directed longitudinally within the sand box so as to agitate and loosen the sand, while another portion thereof will be directed rearwardly within the sand passage 9 so as to suck or draw the sand from the box 8 and direct the blast of sand against the deflector 11 and thence to the discharge pipe.

It will here be noted that the nozzle 34 is 65 devoid of valves so as to render it practically impossible for the passages 35 and 36 to become clogged or otherwise obstructed with sand which may be forced rearwardly by the action of the blast. Moreover, as the diameter of the passages 35 and 36 is uniform and of less diameter than the interior of the bore 37, no pockets or depressions are presented in which sand may find lodgment so that cutting or abrading action of the sand 70 on the nozzle is effectually prevented. Should any grains of sand enter the passages 35 or 36, said grains of sand will be automatically discharged when air is admitted to the blast nozzle, thereby rendering 75 the device self-cleaning.

It will also be noted that the lip 10 not only serves to concentrate the sand on the deflector 18, but by reason of the forward slope of the lower wall of the inlet passage 80 9 at said lip, the sand from the box 8 is prevented from entering the casing when the device is not in use.

The free end of the tubular body portion 85 of the nozzle at the extension 34 thereof is 90

provided with an opening normally closed by a screw or plug 38 by removing which a wire or other flexible instrument may be readily inserted through the opening and 5 through the passages 35 and 36 to facilitate cleaning the same if necessary.

Extending laterally from and preferably formed integral with the flange 24 are spaced ears 39 adapted to receive between them 10 a clamping device preferably in the form of a threaded bolt 40, which latter serves to retain the nozzle in position on the casing. By providing the head of the blast nozzle with the ears 39, the nozzle may be 15 readily removed from the casing to permit cleaning or renewal thereof without the necessity of entirely detaching the bolt 40, it being merely necessary to partially rotate the bolt when the ears may be withdrawn 20 therefrom and the nozzle detached, thereby reducing liability of loss of the fastening device or bolt 40 to a minimum. Should, for any reason, the bolt 40 partially rotate or become loose, the nozzle will not become detached from the casing, owing to the fact that the ears 39 span the bolt and thereby prevent accidental displacement of the nozzle. The ears 39 and bolt 40 also render 25 it practically impossible for the blast nozzle 30 to be positioned incorrectly within the casing as the ears must span the bolt before the nozzle can be inserted.

Attention is here called to the fact that the nozzle is centered within the sand passage 9 by the seat 33 and clamping bolt 40, while the inclined walls 34 of the nozzle proper afford a clearance between the nozzle and the inner wall of the sand passage 9 sufficient to allow the discharge of stones, 40 gravel and other particles from the sand box.

The nipple 6 is preferably secured to the sand box 8 by means of co-acting clamping nuts 41, the walls of which are preferably 45 curved to conform to the curvature of said sand box, as best shown in Fig. 2 of the drawings.

In devices of this character where valves are employed in the blast nozzle, the sand 50 has a tendency to collect back of the valve or in any pockets or depression thereabout and cut or wear away the parts which objectionable feature is entirely obviated in the present construction in that no valve is 55 employed for controlling the blast of air to the sand box. Again in track sanders in general use, the sand has a tendency to cut the interior walls of the casing and where a soft metal lining or jacket is provided for 60 the casing, this jacket is soon cut away by the abrading action of the sand and the pieces thus detached from the casing have a tendency to clog the discharge passage or other portions of said casing. This objectionable feature is also entirely obviated by

the present construction, which, as before stated, directs the sand from the sand box directly against the deflector and thence to the discharge pipe without coming in contact with the walls of the casing. As the 70 deflector may be readily removed and renewed it is apparent that the saving thus effected is material.

Having thus described the invention, what is claimed as new is:

1. A track sander including a casing having sand inlet and discharge passages, a blast nozzle disposed within the inlet passage, means for detachably securing the blast nozzle within the casing, and means 80 independent of the securing means for centering the discharge end of the blast nozzle within the inlet passage.

2. A track sander including a sand box, a casing having sand inlet and discharge passages, one of which communicates with the interior of the box, a deflector and a blast nozzle disposed within the inlet passage and projecting within the sand box, said nozzle being provided with a duct discharging in 90 opposite directions in the same plane into the sand box and against said deflector respectively.

3. A track sander including a sand box, a casing having sand inlet and discharge passages, one of which communicates with the interior of the sand box, a deflector, a blast nozzle having intersecting ducts of uniform diameter, one of which discharges forwardly into the sand box and rearwardly in 100 the same plane against the deflector, and means for centering the blast nozzle within the inlet passage.

4. A track sander including a sand box, a casing having sand inlet and discharge passages, a deflector and a blast nozzle disposed within the inlet passage and having one end thereof projecting within the sand box and provided with unobstructed intersecting ducts disposed at an angle to each other, one 110 of said ducts discharging forwardly into the sand box and rearwardly in the same plane against the deflector.

5. A track sander including a sand box, a casing having sand inlet and discharge 115 passages, a blast nozzle disposed within the casing and having one end thereof provided with a depending enlargement having intersecting ducts formed therein, one of which discharges into the sand box and interior of 120 the casing, respectively, a deflector, and a contracted throat arranged within the inlet passage for directing the sand against the deflector.

6. A track sander including a sand box, a 125 casing having sand inlet and discharge passages, the wall of the inlet passage being curved upwardly to form a lip defining a contracted throat, a blast nozzle arranged within the inlet passage and discharging 130

- into the sand box and interior of the casing, respectively, and a deflector arranged opposite the contracted throat.
7. A track sander including a sand box, a casing having sand inlet and discharge passages, a blast nozzle removably fitted within the casing and having a depending extension provided with intersecting ducts, one of which discharges into the interior of the sand box and casing, respectively, a fastening device carried by the casing and engaging the blast nozzle, and means for permitting the removal of the blast nozzle without detaching the fastening device.
8. A track sander including a sand box, a casing having sand inlet and discharge passages, a blast nozzle disposed within the casing and having a depending extension centered within the inlet passage and provided with intersecting ducts, one of which discharges into the sand box and interior of the casing, respectively, a screen carried by the blast nozzle, and means for detachably securing the blast nozzle to the casing.
9. A track sander including a sand box, a casing having sand inlet and discharge passages, one of which communicates with the interior of the sand box and is provided with a curved wall defining a contracted throat, a blast nozzle disposed within the casing and having a depending portion projecting within the sand box and provided with intersecting ducts disposed at an angle to each other, one of said ducts discharging into the sand box and interior of the casing at said throat, a deflector adapted to receive the impact of the blast of sand and direct the sand into the discharge passage, and means for securing the blast nozzle in position on the casing.
10. A track sander including a sand box, a casing having sand inlet and discharge passages, a fastening device secured to the casing, a blast nozzle carried by the casing and provided with intersecting passages discharging into the sand box and interior of the casing, respectively, and spaced ears carried by the nozzle and co-acting with the fastening device for detachably securing the blast nozzle in position on the casing.
11. A track sander including a sand box, a casing secured to the sand box and having sand inlet and discharge passages, a blast nozzle including a tubular body portion having a depending extension spaced from the walls of the inlet passage and provided with intersecting ducts, one of which discharges into the sand box and interior of the casing, respectively, and a plug forming a closure for one end of the nozzle, the diameter of the ducts being uniform and of less diameter than the interior of the nozzle.
12. A track sander including a sand box, a casing secured to the sand box and provided with sand inlet and discharge passages, and a blast nozzle carried by the casing and including a tubular body portion having one end thereof provided with a depending extension projecting within the sand box and formed with intersecting ducts, one of which communicates with the interior of the nozzle and the other with the interior of the sand box and casing, respectively, the intermediate portion of the nozzle being deflected upwardly out of the path of the sand from the adjacent duct.
13. A track sander including a sand box, a casing having sand inlet and discharge passages, the inlet passage communicating with the interior of the sand box and having one wall thereof curved upwardly to form a lip defining a contracted throat, a deflector arranged opposite the throat, a blast nozzle having one end thereof provided with a depending extension formed with intersecting ducts, one of which communicates with the interior of the nozzle and the other with the interior of the sand box and casing, respectively, said extension of the nozzle projecting within the sand box and having a detachable closure at one end thereof, and a strainer arranged at the other end of the nozzle.
14. A track sander including a sand box, a casing having sand inlet and discharge passages, a nozzle arranged within the casing and having one end thereof provided with a head and its other end formed with a depending extension projecting within the sand box and provided with intersecting ducts, one of which communicates with the interior of the nozzle and the other with the interior of the sand box and casing, respectively, a bushing threaded on the head of the nozzle and provided with a shoulder, a strainer having a flange resting on the shoulder, and a nipple engaging the bushing and bearing against the flange of the strainer.
15. A track sander including a sand box, a casing having sand inlet and discharge passages and provided with a flat face having a circumferential rib, a blast nozzle extending within the casing and having one end thereof provided with a depending extension projecting within the sand box and provided with intersecting ducts, the other end of the nozzle being formed with a head having a groove therein to receive the rib, a bushing engaging the head, a strainer carried by the bushing, and a nipple engaging the bushing and bearing against the strainer for locking the latter against accidental displacement.
16. A track sander including a sand box, a casing having sand inlet and discharge passages, the inlet passage having its upper wall formed with a seat and its lower wall deflected upwardly and forwardly to form a terminal lip defining a contracted throat,

5 a blast nozzle engaging said seat and spaced from the lower wall of the inlet passage, and a deflector arranged opposite the contracted throat of the inlet passage and having its face disposed at an angle to the longitudinal axis of the discharge passage.

10 17. A track sander including a sand box, a casing having sand inlet and discharge passages, a blast nozzle disposed within the casing and having one end thereof provided with a depending extension formed with intersecting ducts, one of which discharges into the sand box and into the interior of the casing, one wall of the inlet passage 15 being curved upwardly to form a contracted throat spaced from the adjacent end of the extension of the nozzle, and a deflector arranged opposite the contracted throat for directing the sand into the discharge passage.

20 18. A track sander including a casing having sand inlet and discharge passages, a nozzle disposed within the casing and including a tubular body portion having a 25 depending head, the side walls of which are inclined downwardly and spaced from the adjacent walls of the inlet passage, said extension being provided with intersecting ducts of uniform diameter and of less diameter than the interior of the body portion, a 30 closure secured to the nozzle above the depending portion thereof, and a strainer disposed in the path of the air passing through said nozzle.

35 19. A track sander including a sand box, a casing having sand inlet and discharge passages, one of which communicates with the interior of the box, a deflector, and a

blast nozzle disposed within the inlet passage and projecting within the sand box, 40 said nozzle being provided with intersecting ducts, one of which discharges in opposite directions into the sand box and against the deflector, respectively.

45 20. A track sander including a sand box, a casing having sand inlet and discharge passages, one of which communicates with the interior of the box, a deflector, and a blast nozzle arranged within the inlet passage, said blast nozzle being provided with 50 a duct discharging in opposite directions into the sand box and against said deflector.

55 21. A track sander including a sand box, a casing having sand inlet and discharge passages, the wall of the inlet passage being extended upwardly to form a lip, a deflector arranged within the casing and spaced from the lip, and a blast nozzle disposed within the inlet passage, said blast nozzle being provided with a duct discharging forwardly 60 into the sand box and rearwardly over said lip against the deflector.

65 22. A track sander including a casing having inlet and discharge passages, a deflector arranged within the casing, and a blast nozzle disposed within the inlet passage, said blast nozzle being provided with a duct discharging forwardly through the open end of the inlet passage and rearwardly against the deflector.

70 In testimony whereof I affix my signature in presence of two witnesses.
